UNITED STATES PATENT OFFICE.

HENRY PEARSON, OF SPRINGFIELD, MASSACHUSETTS.

RAILWAY SLEEPING-CAR.

SPECIFICATION forming part of Letters Patent No. 544,547, dated August 13, 1895.

Application filed January 14, 1895. Serial No. 534,822. (No model.)

To all whom it may concern.

Be it known that I, HENRY PEARSON, a citizen of the United States of America, residing at Springfield, in the county of Hampden and 5 State of Massachusetts, have invented new and useful Improvements in Railway Sleeping-Cars, of which the following is a specification.

This invention for improvement in railway 10 sleeping-cars consists in the interposition of means of connection or engagement between the berth and the hoisting-cables therefor, (of which there are several,) of means whereby on the occasion, from any cause, of the 15 slackening of the cable when the berth is being moved, the slack will be taken up, leaving the cable taut and without liability of becoming kinked or of in any manner impeding the lowering or raising actions.

20 The invention consists, in substance, in the combination and arrangement of a means of attachment or engagement between the berth and each of the cables therefor, consisting of a casing secured to the berth, a part movable 25 therein to which the cable is connected, and a spring for forcing the movable part downwardly in the casing, and against the stress of which is the draft of the cable.

Reference is to be had to the accompanying 30 drawings, in which Figure 1 is a perspective view showing a part of a "berth-pocket," as termed, the berth therein, and the trap-door or cover which may cover the berth-pocket and also serves as the supporting upright 35 for the berth, the location of the cable and berth connection being shown. Fig. 2 is a vertical sectional view, on a larger scale, of the aforesigned parts, the trap-door being in its upright position, the berth being raised 40 out from the berth-pocket, and the details of construction of the cable and berth take-up connection being shown. Fig. 3 is a vertical sectional view similar to Fig. 2, but showing the trap-door as in its horizontal position over 45 the berth which is in the berth-pocket, the movable parts of the take-up connection being, however, in different relative positions. Fig. 4 is a face view of an end portion of the berth at the corner thereof.

50 The trap-door A, which has substantially a hinge connection at one end of the berth-pocket C, has the sheave-cases a, (with sheaves

therein,) over which the cables m pass, the cables running thereto from the hoisting-drum, (not shown,) they being guided by the 55 sheaves at b, and the cables run from the sheaves on the trap-doors to their connection with the ends of the berth, all as fully illustrated, described, and claimed in an application for Letters Patent filed by me December 60 31, 1894, Serial No. 533,434.

On the berth D, near each corner thereof, is the casing and guide B, it having the plate 20, by means of which it may be secured by screws, as shown, and it has the downwardly-opening bore d, with the contracted opening f at its upper end, whereby is formed the internal shoulder 22. Within this bore is the tube g, externally threaded at its lower end. A sleeve h surrounds the tube, being supported by the nut i, which screws onto the threaded lower end of the tube. The spiral spring j is applied between the sleeve h and the internal shoulder 22. The terminal of the cable is passed through the tube and has 75 its lower end enlarged in any adequate and practicable manner, so as to be engaged with the lower end of the sleeve, all as plainly shown in the drawings.

The weight of the berths is greatly in excess of the recoil of the springs j. Hence when the berth is in suspension the springs will be compressed to their maximum. When the berth is lowered into the berth-pocket and the trap-door is swung downward, a slackening of the cable ensues, because of the fact that the point of running engagement which the cable has with the sheave at b is offset from a plane parallel with the face of the trap-door which intersects the center of swinging movement at y of the trap-door. Therefore, as the door is swung downwardly and the distance between the sheaves at a and b slightly decreases, the tendency of the cable to slacken will be overcome by the action of 95 the compensating connection described.

Having thus described my invention, what I claim, and desire to secure by Letters Patent, is—

1. In a railway sleeping-car in combination, 100 the berth having at its end a vertically applied casing or tubular guide, a part movably guided therein, the hoisting cable having its end entered through an opening therefor in

the top of said tubular guide and connected to the said movable inclosed part, and the spring for forcing the movable part downwardly in said tubular guide, in combination 5 with the trap-door which has one end in pivotal engagement with the bottom of the car whereby it is convertible into an upright and which is provided with a sheave over which the said cable has a guiding and supporting 10 engagement, said sheave rotating in a plane which is offset from the axis of swinging movement of the trap-door, all substantially as set forth.

2. In a railway sleeping-car, the combina-

tion with the berth having the casing secured 15 thereto, of a tube having a nut secured to its lower end, the cable passed through an opening in the top of the casing and through and connected with said tube, the spiral spring within the casing, surrounding said tube and 20 cable, supported by the nut, and having an upper end bearing against a stop therefor within the casing, substantially as described.

HENRY PEARSON.
